UNITED STATES PATENT OFFICE.

CHARLES T. WESTLAKE, OF ST. LOUIS, MISSOURI, ASSIGNOR TO THE
TRANSOM DRAFT-GEAR COMPANY, OF ST. LOUIS, MISSOURI, A
CORPORATION OF DELAWARE.

DRAFT-GEAR FOR RAILROAD-CARS.

No. 841,202.

Specification of Letters Patent.

Patented Jan. 15, 1907.

Application filed October 24, 1906. Serial No. 340,379.

To all whom it may concern:

Be it known that I, CHARLES T. WESTLAKE, a citizen of the United States, residing at St. Louis, in the State of Missouri, have invented 5 a new and useful Improvement in Draft-Gear for Railroad-Cars, of which the following is a specification.

My invention relates to draft-gear for a railroad-car, and particularly to that class of 10 draft-gear in which a single spring arranged with follower-plates in alinement with the longitudinal center of the car is applied to a metallic block or housing fixed between the middle longitudinal car-sills or directly to 15 the body-bolster, and has for its object to reduce the width and consequent weight of the block or bolster by dispensing with the usual outlying flanges or lugs formed at the sides thereof for limiting the outer movement of 20 the follower-plates and also to render the draw-bar of this class of draft-gear self-centering.

The invention consists in means for limiting the outer movement of the follower- 25 plates at the central part of the bolster or housing therethrough for the spring combined with auxiliary self-centering springs between the bolster and the draw-bar of 30 the draft-gear, as hereinafter described and claimed, reference being had to the accompanying drawings, forming part of this specification, whereon—

Figure 1 is a horizontal section through the middle portion of a car-body bolster with 35 my improved draft - gear applied thereto; Fig. 2, a vertical longitudinal section thereof on line 2 2 in Fig. 1; Fig. 3, a vertical transverse section through the same on line 3 3 in Fig. 2, omitting the draw-bar; and Fig. 4, a 40 horizontal section on line 4 4 in Fig. 3 through the front or "buffing" follower-plate detached.

Like letters and numerals of reference denote like parts in all the figures.

45 *a* represents the middle portion of a metallic car-body bolster having the body center-plate 1 on its under side and secured to the longitudinal sills of the car in the usual manner.

50 Transversely through the web 2 (or middle portion) of the bolster *a*, which in the present case is I-shaped in cross-section, is formed a tubular-shaped housing 3, which projects

longitudinally from each side of the web 2 in central alinement to the longitudinal center 55 of the car for the play of the spring 4 (indicated by dotted lines) therethrough, the housing 3 consisting, preferably, of two opposite longitudinal circular segmental walls communicating through their top and bottom intermediate spaces with suitably-shaped openings 3', formed through the web 2 for the passage therethrough of the draw-bar yoke, as hereinafter more particularly referred to.

b and *b'* are follower-plates, which in the assembled position of the parts bear against the front and rear ends, respectively, of the spring 4.

c is the draw-bar, which butts at its inner 70 end against and is radially adjustable thereat horizontally to the front follower-plate *b*.

To the draw-bar *c*, adjacent to its bearing against the front follower-plate *b*, are jointed by a pin 5 or otherwise the arms 6 of a yoke 75 *d*, which embraces the follower-plates *b* *b'* and intermediate spring 4 in the usual manner, the arms 6 passing freely through the aforesaid openings 3' in the web 2 of the bolster *a*. Each follower-plate *b* *b'*, which in the 80 present case is circular, is formed circumferentially at right angles thereto with two opposite arms 7, which are of suitable length according to that of the spring 4, each arm 7 having at its free end an outwardly-projecting 85 flange or lug 8, and at a suitable distance therefrom is a second outwardly-projecting lug 9, the distance between the lugs 8 and 9 being equal to the length of the housing 3 plus the "draft" and buffing play of the fol- 90 lower - plates *b* *b'*, respectively, or, if desired, in lieu of the limiting-lugs 9 the inward movement of the follower-plates *b* *b'* may be limited by a bar 10, projecting within the spring 4 from the inside of one of the said 95 plates, with its free end at a distance from the other plate equal to the said play, as indicated by dotted lines in Fig. 1, the bar 10 in such case transmitting the thrust of the inward-moving follower-plate to the opposite follower-plate and thence by the arms of the latter and their end lugs 8 to the bolster *a*, or the bar 10 may lie loosely within the spring 4 between the plates *b* and *b'*.

In the assembled and normal positions of 105 the parts the arms 7 of the front follower-

plate (which are previously inserted within the openings 3' of the bolster and adjusted on the inside of the housing 3) project horizontally through the housing 3 on the front side of the bolster *a* with their end flanges 8 in engagement with the rear edge of the housing 3 and the arms 7 of the rear follower-plate *b'* through the housing 3 on the rear side of the bolster *a* with their end flanges 8 in engagement with the front edge of the housing 3, in which position of the follower-plates *b* *b'* the spring 4 bears circumferentially against or in proximity to the inside of their arms 7, the adjoining edges whereof, respectively, will be in contact with each other and the opposite edges in proximity to the side edges of the yoke *d*, whereby the follower-plates *b* and *b'* are held in place circumferentially, while free to slide longitudinally within and through the housing 3 at all times.

In operation when pulling on the draw-bar *c* the rear follower-plate *b'* is forced inward by the yoke *d*, so as to compress the spring 4 against the front follower-plate *b*, which is held in place immovably by its end flanges 8 in engagement with the rear edge of the housing 3, the inward movement of the follower-plate *b'* being limited by the lugs 9 on its arms 7 engaging with the rear edge of the housing 3. Similarly, when buffing the front follower-plate *b* is forced inward by the draw-bar *c* and compresses the spring 4 against the rear follower-plate *b'*, which is held by the end flanges 8 in engagement with the front edge of the housing 3, the inward movement of the front follower-plate *b* being limited by the lugs 9 of its arms 7 engaging with the said edge.

By this construction the outer movements of the follower-plates *b* *b'* of the draft-gear are limited by surface portions of the bolster in proximity to its longitudinal center, and thereby obviate the necessity of forming flanges or lugs therefor at a distance from the said center corresponding to the length of the spring plus the thickness of the follower-plates, as heretofore, whereby the weight of the bolster is considerably reduced, the draft-gear rendered more compact, and economy effected.

Projecting beyond the inner end of the draw-bar *c*, preferably at the bottom and at an equal distance on each side of the longitudinal center thereof, is a pocket 11, which is adapted to receive the front end and adjacent portion of an auxiliary spring 12, having its rear end in the assembled position of the draft-gear bearing constantly against the front side of the bolster *a* or adjacent part of the housing 3, whereby the draw-bar *c*, when constrained radially to its bearing against the front follower-plate *b* to either side of the longitudinal center of the car, on being released will be automatically returned to its normal position or self-centered.

I do not limit myself to a single-spring draft-gear as above described, as a similar construction of follower-plates with their arms and limiting-stops may be applied to other classes of draft-gear, such as that described in United States Letters Patent granted to Harry M. Pflager January 10, 1905, No. 779,559, in which the springs are arranged in the same horizontal plane, one on each side of the longitudinal center of the car, in which case the auxiliary springs 12 between the draw-bar *c* and bolster *a*, described in the present case, are dispensed with.

What I claim as my invention, and desire to secure by Letters Patent, is—

1. In draft-gear for a railroad-car, the combination of a spring, a suitable housing fixed to the car and having a passage longitudinally therethrough for the spring, a follower-plate adapted to bear against the front end of the spring, a follower-plate adapted to bear against the rear end of the spring, a draw-bar adapted to engage the front follower-plate, a yoke coupled to the draw-bar and embracing the said spring and plates, two opposite arms projecting from the inside of each of the said plates at right angles thereto and adapted to slide longitudinally through the housing, a flange on the free end of each of the said arms, the said flanges on the arms of the front follower-plate being adapted to engage the rear edge of the housing and the flanges on the arms of the rear follower-plate to engage the front edge of the housing in the normal position of, and for limiting the outer movement of the said plates, and means for limiting the inner movement of the said plates, substantially as described.

2. In a draft-gear for a railroad-car, the combination of a spring, a suitable housing fixed to the car and having a passage longitudinally therethrough for the spring, a follower-plate adapted to bear against the front end of the spring, a follower-plate adapted to bear against the rear end of the spring, a draw-bar adapted to engage the front follower-plate, a yoke coupled to the draw-bar and embracing the said spring and plates, two opposite arms projecting from the inside of each of the said plates at right angles thereto, and adapted to slide longitudinally through the housing, a flange on the free end of each of the said arms, the said flanges on the arms of the front follower-plate being adapted to engage the rear edge of the housing, and the flanges on the arms of the rear follower-plate to engage the front edge of the housing in the normal position of and for limiting the outer movement of the said plates and a lug on the said arms respectively adapted to engage the said edges for limiting the inner movement of the said plates, substantially as described.

3. In draft-gear of the character described, the combination of a spring, a suitable housing having a passage longitudinally therethrough for the spring, a follower-plate
5 adapted to bear against the front end of the spring, a follower-plate adapted to bear against the rear end of the spring, a draw-bar adapted to engage the front follower-plate and radially movable horizontally thereto, a
10 yoke coupled to the draw-bar and embracing the said spring and plates and a spring inter-

posed between the inner end of the draw-bar at each side of its longitudinal center and the said housing, substantially as described and for the purpose set forth. 15

In testimony whereof I have signed my name to this specification in the presence of two subscribing witnesses.

CHARLES T. WESTLAKE.
